[57] **CLAIM**

The ornamental design for a jewelry component, as shown and herein described.

DESCRIPTION

FIG. 1 is a perspective view of a jewelry component showing my new design in a position of use, the broken line showing of the adjacent components are for illustrative purposes only and form no part of the claimed design;

FIG. 2 is an enlarged perspective view;

FIG. 3 is a top plan view of FIG. 2;

FIG. 4 is a side elevational view of FIG. 2, the opposite side being a mirror image;

FIG. 5 is an enlarged perspective view of a jewelry component showing a second embodiment of my new design;

FIG. 6 is a side elevational view of FIG. 5, the opposite side being a mirror image;

FIG. 7 is a right side elevational view of FIG. 5, the opposite side being a mirror image;

FIG. 8 is a perspective view of a jewelry component showing a third embodiment of my new design, the broken line showing of the adjacent components are for illustrative purposes only and form no part of the claimed design;

FIG. 9 is an enlarged perspective view of FIG. 8;

FIG. 10 is a top plan view of FIG. 9;

FIG. 11 is a side elevational view of FIG. 9, the opposite side being a mirror image;

FIG. 12 is a perspective view of a jewelry component showing a fourth embodiment of my new design;

FIG. 13 is a side elevational view of FIG. 12, the opposite side being a mirror image;

FIG. 14 is a right side elevational view of FIG. 12, the opposite side being a mirror image;

FIG. 15 is a perspective view of a jewelry component showing a fifth embodiment of my new design, the broken line showing of the adjacent components are for illustrative purposes only and form no part of the claimed design;

FIG. 16 is an enlarged perspective view of FIG. 15;

FIG. 17 is a top plan view of FIG. 16;

FIG. 18 is a side elevational view of FIG. 16, the opposite side being a mirror image;

FIG. 19 is a cross sectional view taken along the lines 19—19 of FIG. 17;

FIG. 20 is a perspective view of a jewelry component showing a sixth embodiment of my new design;

FIG. 21 is a side elevational view of FIG. 20, the opposite side view being a mirror image; and,

FIG. 22 is a right side elevational view of FIG. 20, the opposite side view being a mirror image.
